UNITED STATES PATENT OFFICE.

BENJAMIN E. GETCHELL, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

ELECTRIC-SWITCH CONSTRUCTION.

Application filed September 18, 1922. Serial No. 588,834.

To all whom it may concern:

Be it known that I, BENJAMIN E. GETCHELL, a citizen of the United States of America, residing at Plainville, Connecticut, have invented a new and useful Electric-Switch Construction, of which the following is a specification.

My invention relates to what are usually called safety switches in which the switch elements are enclosed in a receptacle or box and an external handle is provided for operating the switch.

The main object of my present invention is to provide a simple but inexpensive construction which is reliable. Another object is to provide a construction in which the switch parts are readily accessible when the box is open. Another object is to provide a construction which has few parts and is therefore not likely to get out of order. Another object is to provide a simple but effective method of constructing and mounting the handle and operating mechanism in such a manner that these parts co-act to provide an interlocking construction whereby the switch must first be thrown to off position before the cover can be opened and whereby, when the cover is opened, the handle is entirely disengaged from operative relation with the switch and the switch cannot be operated until the cover is again closed to operatively engage the handle with the switch.

In the preferred form of my invention I mount the switch contact and a movable switch member on an insulating base in the body of the box or receptacle and the handle and operating mechanism are mounted on the cover so as to provide a means of connection between the handle and the movable member of the switch when the box is closed but so as to entirely disconnect the handle from the switch when the box is open.

Fig. 1 is a face view of a switch embodying the improvements of my invention showing the principal interior parts dotted.

Fig. 2 is a side view of the construction showing the quick break mechanism in dotted outline.

Fig. 3 is an end view of the construction, and

Fig. 4 is a side view and partial section with the cover removed.

Fig. 5 is a longitudinal sectional view on

a larger scale showing the handle mounting and quick break mechanism.

Fig. 6 is a fragmentary view showing the quick break mechanism looking from the left of Fig. 5, the parts being in the open circuit position.

Fig. 7 is a similar view showing the parts in the closed circuit position in which they are interlocked so as to prevent opening of the cover.

Fig. 8 is a perspective view showing details of the handle mounting and quick break mechanism.

The insulating base 10 in the form of construction shown carries stationary jaws 11 and 12. Between these are mounted movable contact blades 13 which are carried by an insulating cylinder 14. This cylinder is provided with hubs or shafts 15 pivoted in side brackets 16. A spring pressed plunger 17 may be provided to co-act with socket or recess 18 in one of the brackets so as to yieldingly hold the cylinder in place. The cylinder is also provided with a projecting pin 19 adapted to oscillate in a slot 20 in one of the brackets.

The receptacle or box consists of a body portion 21 and a cover 22 which are connected by a hinge member 23. The spring catch 24 may be provided to hold the cover in its closed position. One side 25 of the box is preferably cut lower than the ends and the opposite side, and the cover is provided with a deep overlapping portion 26 so that when the cover is open the switch mechanism is more completely exposed and the handle is disconnected from the switch. This cover extension 26 carries the handle 27 and the quick-break mechanism of the switch. The member 28 on the inside of the box constitutes an interlocking member in connection with the pin 19. Inside of this member 28 is a cam-like member 29 connected to the handle member 27.

The handle is mounted to oscillate in the side of the cover. The washer 30 is connected to rotate with the handle. Projections 31 may interlock with the washer 30. The washer 32 on the inside of the cover is similar to 30 and is spaced apart from it by a washer 33 which fits in an opening in the side of the cover to form a bearing for the handle. A washer 34 overstands the member 28 and the parts are all held to-

gether preferably by rivets 35 which pass through the cam 29, the spacers 36 and 37 and the washers 32, 33 and 30, the heads of the rivets preferably being seated in the recesses 38 in the handle member. The handle member may be removably held in place by a screw 39 and a spring washer 40 or it may be permanently secured by means of rivets. The member 28 is provided with a lug 41 adapted to co-act with shoulders 42 in the cam member 29 when the cam member is rotated by means of the handle.

The operating member 28 is provided with two shoulders 43 and 44 adapted to engage the projecting member 19 of the switch blade carrier cylinder. The rod 45 is pivoted at one end to the member 28 and guided at the other end by a claw-like forked member 46 which is secured to the cover. Referring to Figs. 6 and 7, it will be seen that the slotted claw-like abutment 46 makes it possible to readily secure the rod 45 and the spring 47 in operative position as well as to easily and quickly remove or replace a spring should this be necessary.

For convenience in manufacture the rod 45 may be formed of two pieces of sheet metal. The spring 47 surrounds a part of the rod 45 and is compressed between the head of the rod adjacent the member 28 and the guide 46. The shoulder 48 of the member 28 engages the spring in the open circuit position shown in Fig. 6 so as to limit the throw in that direction and the shoulder 49 serves as an abutment against the spring in the closed circuit position in Fig. 7.

With the parts in the position shown in Figs. 1 to 6 the cover may be opened (the latch 24 if present being released). To close the switch when the cover is closed the handle is moved clockwise as viewed in Fig. 2 or anti-clockwise as viewed in Fig. 6 until the cam member 29 picks up the projection 41 and thus rotates the member 28 and compresses the spring 47. About the same time that the spring 47 reaches a maximum compression the shoulder 43 picks up the pin 19 so that when the spring snaps the member 28 over to the position shown in Fig. 7 it carries with it the pin 19 and the cylinder 14 with the switch blades 13 closing the switch with a snap action. In the closed circuit position the pin 19 is directly over the member 28 which, of course, is carried by the cover so that the cover cannot be opened with the switch in the closed circuit position.

To open the switch the handle is moved in the reverse direction i. e. so as to move the parts from the position shown in Fig. 7 to the position shown in Fig. 6. In doing so the cam member 29 picks up the projection 41, rotates the member 28 to compress the spring 47 and the shoulder 44 engages the pin 19 at about the time the spring is compressed to its maximum degree. Further

rotation of the member 28 carries the rod 45 to the other side of the center line and the spring suddenly snaps the switch to the open circuit position whereupon the cover may be opened if desired.

Referring particularly to Fig. 8, it will be seen that the quick-make and quick-break mechanism constitutes practically a unit in itself. This unit is made up almost entirely of stampings and flat washers several of which are duplicates.

Washers and stampings of this character completely obviate variation and may be readily and accurately assembled as a unit by means of the simplest mechanical operations and at a minimum cost. Further, this construction allows as many spacing washers as may be desired to meet mechanical conditions in different sizes or styles of switches.

Although the handle member 27 is shown provided with a separate knob handle, it may be constructed of a single piece of sheet metal having the outer end suitably formed so as to form an integral handle.

It is obvious that this switch operating means, including the spring 47, the rod 45 and the forked bracket 46 may be mounted as a complete unit on a suitable separate plate or bracket which may be secured to the side of a switch box. It may be set up alongside of a switch if so desired or the separate plate may be omitted and the operating mechanism may be secured directly to the side of an enclosing box as shown.

As shown in the drawings, the operating plate 28 is cut out at one side for co-operation with the projecting pin 19 carried by the switch blade cylinder 14. It is obvious that other forms of lost motion connection may be made between these parts and that the plate may be readily arranged for a lost motion connection with various types of switches, for instance, it would be a simple mechanical matter to connect this plate 28 with the blades of a common knife switch.

I claim:

1. An enclosed switch construction comprising box members, a switch mounted therein, one of said box members having a bearing opening, a bearing washer in said opening, a handle member outside of said box, a guard washer inside of said box adjacent said bearing washer, a lost-motion washer, an operating plate mounted on said lost-motion washer and having operable connection therewith, a cover washer larger in diameter than said lost-motion washer, and rivets passing through all of said washers and said handle for securing them together and in position.

2. An enclosed switch comprising a box body open at one side, a switch mounted therein, a cover having a side overlapping the opening in the body, a handle and operating member carried by said side, a lost

motion connection between said handle and said operating member, a spring carried by the cover for snapping said plate from one position to another and operative means of connection between said operating member and said switch serving to prevent the opening of the cover when the switch is closed.

3. An enclosed switch comprising a box body, a switch mounted therein including 10 side brackets, a cylinder with switch contacts carried thereby, a pin projecting from said cylinder through one of said brackets, a cover for said box, quick break operating mechanism carried by said cover including 15 an operating member adapted to engage said projection to open the switch, said projection being adapted to engage said operating member to hold the cover closed when the switch is closed.

20 4. An enclosed switch construction comprising a box body, a switch mounted therein, a cover, a handle and quick break mechanism carried thereby including a switch operating spring and a support for said 25 spring, the said spring and said support serving as a stop for the mechanism in the open circuit and closed circuit positions.

5. An enclosed switch construction comprising a box body, a switch mounted therein, a cover, switch operating mechanism carried by the cover including a handle, an operating plate, a lost motion connection between the handle and said plate and a spring pressed member serving as a stop for 35 said plate.

6. An enclosed switch comprising a box having a cover and body, a switch mounted therein consisting of a base, stationary switch contacts carried thereby, brackets secured to opposite sides of said base, one of said brackets having a slot, a switch member pivoted in said brackets independently of said box and having a pin projecting through said slot, and an operating 40 handle and quick break mechanism carried by one part of said box and adapted to contact with said pin to operate said switch member.

7. In an enclosed switch construction, a 50 box member having an opening, a bearing member mounted in said opening, a washer on each side of said bearing member, an operating plate, a lost-motion member having operable connection with said plate, and rivets passing through said lost-motion member and said washers for holding said parts together.

8. In an enclosed switch construction a 60 box member having an opening, a bearing member mounted in said opening, washers on opposite sides of said bearing member, rivets passing through said washers holding them together and a switch operating member having positioning recesses for the 65 heads of said rivets.

9. In an enclosed switch construction a box member, a handle, an operating member having a lost motion connection with said handle, a slotted claw-like abutment secured to said box member, a spring pressed rod 70 connected to said operating member and removably guided in said abutment and serving as a step for said plate.

10. In an electric switch, an enclosing box, a switch in said box having a base and 75 a pivoted two-position insulating member secured to said base, switch blades carried by said insulating member, a lateral projection carried by said insulating member, a cover for said switch box, switch operating means carried by said cover including 80 a shouldered operating plate adapted to engage with the projection carried by the insulating member to hold the cover closed when the switch is closed.

11. In an electric switch, an enclosing box, a switch in said box including a pivoted two-position member of insulating material, switch blades carried by said member, a lateral projection carried by said member, 90 a cover for said switch box, switch operating means carried by said cover including a shouldered operating plate for engagement with the projection carried by the insulating member, the said projection being 95 adapted to be moved to a position under the shouldered operating plate when switch is closed to prevent the opening of the cover and the switch operating means being adapted to rotate the said projection to free 100 the cover when the switch is moved to off position.

12. In an electric switch, a quick-make and quick-break construction including a support, a bearing opening in said support, a peripheral bearing washer in said opening, a side bearing washer at each of the opposite sides of said support, a switch operating handle, a switch operating plate having an opening, a journal washer in said opening having a lost-motion connection with said operating plate, a side supporting washer for said operating plate, means for securing said washers, switch handle and operating plate together, a spring pressed arm pivoted at one end to said operating plate and supported at the other end by stationary means and means for a lost motion connection between said operating plate and the blades of an electric switch.

13. In an electric switch, a quick-make and quick-break construction including a support, a switch operating handle having a bearing in said support, a two position switch operating plate at the opposite side of said support and having an opening coaxial with said handle support, a bearing washer in the opening and in the plane therewith, said bearing washer and said operating plate having a lost-motion con- 120 125 130

nection, spring means for forcing said operating plate into its alternative positions of rest and washers for spacing the said operating plate away from said support, the said operating plate having a lost-motion connection with an electric switch.

14. In an electric switch, a quick-make and quick-break construction including a support, a switch operating handle journaled in said support, bearing washers and spacing washers co-axial with said handle bearing and secured together with said handle, a two-position switch operating plate co-axial with said handle bearing having a lost motion connection with one of

said washers and a lost motion connection with an electric switch and spring means for forcing said switch operating plate into its alternative positions, the said handle, bearing washers, spacing washers and switch operating plate being constructed from sheet metal stampings.

15. In an electric switch, a sheet metal handle, a bearing washer, a spacing washer, a lost-motion washer, a sheet metal operating plate mounted on said lost-motion washer, an end washer, and securing means passing through all of said washers and said handle for securing them together.

BENJAMIN E. GETCHELL.
